(57) **CLAIM**

The ornamental design for an electricity meter, as shown and described.

DESCRIPTION

1.1 is a front perspective view of the electricity meter showing the new design.

1.2 is a rear elevation view thereof.

1.3 is a right side elevation view thereof.

1.4 is a top elevation view thereof.

1.5 is a front elevation view thereof.

1.6 is a left side elevation view thereof.

1.7 is a bottom elevation view thereof.

The features shown in broken lines in the drawings depict portions of the design that form no part of the claimed design.
